UNITED STATES PATENT OFFICE.

RICHARD E. ELLIS, OF SYRACUSE, NEW YORK, ASSIGNOR OF ONE-HALF
TO CHARLES T. McCORD, OF SYRACUSE, NEW YORK.

MOLD FOR MAKING PLUG-TOBACCO.

SPECIFICATION forming part of Letters Patent No. 773,008, dated October 25, 1904.

Application filed September 17, 1903. Serial No. 173,547. (No model.)

To all whom it may concern:

Be it known that I, RICHARD E. ELLIS, a citizen of the United States, and a resident of Syracuse, in the county of Onondaga, in the State of New York, have invented new and useful Improvements in Molds for Making Plug-Tobacco, of which the following, taken in connection with the accompanying drawings, is a full, clear, and exact description.

10 The object of this invention is to provide simple and efficient means for expeditiously and economically molding and compressing into plug shape cigar-cuttings, scrap-tobaccos, and also leaf-tobacco with or without 15 said cuttings and scraps and without requiring the tobacco to be put up in separate bundles of predetermined size or weight before applying the tobacco to the mold; and to that end the invention consists in the novel construction and combination of a mold-frame 20 provided with vertical knives extending across the interior of said frame and disposed with their cutting edges at their tops and a follower of the same perimeter as the interior 25 of the said mold-frame and entering the same and provided with creases coinciding with the aforesaid knives and extending part way the depth of the follower to meet the integral top portion thereof, and thereby cut the tobacco throughout the depth of the layer, all 30 as hereinafter more fully described and as summed up in the claim.

In the annexed drawings, Figure 1 is an elevation, partly in section, showing the operation of molding and compressing the tobacco as aforesaid. Fig. 2 is a transverse section illustrating the mold charged with the tobacco to be compressed therein. Fig. 3 is a plan view of the mold, and Fig. 4 is a perspective view of the attaching end of one of the knives.

Similar letters of reference indicate corresponding parts.

A represents the mold-frame, which is provided with two series of vertical knives *a' a'*, disposed at right angles to each other and extending across the interior of said frame and

secured thereto in any suitable manner, preferably by means of tongues *b*, projecting from the ends of the knives and inserted into 50 grooves *c* in the inner sides of the frame and extending from the bottom of the frame part way toward the top, as shown in Fig. 4 of the drawings. The knives of one series are provided with vertical grooves *d d*, into which 55 are inserted the knives of the other series. Each of the knives is disposed with its cutting edge upward, as shown in Fig. 1 and Fig. 2 of the drawings.

B represents a horizontal press-bed upon 60 which the aforesaid mold-frame is mounted preparatory to molding and pressing the tobacco, which is deposited into the pockets *e e*, formed between the knives, as shown in Fig. 2 of the drawings. The knives extend through 65 the entire depth of the mold-frame and are supported on the press-bed, which forms the bottoms of the pockets *e e*.

C denotes the follower, which is of the same perimeter as the interior of the mold-frame 70 A, so as to allow it to enter into said mold-frame. This follower is detached from the press-head and provided in its under side with creases *l l*, which coincide with the positions of the knives *a' a'*, so as to allow them 75 to enter into said creases. The creases extend only part way the depth of the follower and are terminated by the integral top portion of the follower.

In the operation of molding and compressing the loose tobacco into plug shape said tobacco is deposited into the mold and partly spread over the tops of the knives, as shown in Fig. 2 of the drawings. Then the press is operated to force the follower down into 85 the mold. The descent of the follower causes the knives to cut through the overlying tobacco and to meet the integral top portion of the follower, as shown in Fig. 1 of the drawings. This insures a perfect separation of 90 the compressed plugs from each other.

If desired to expedite the process of molding and compressing the tobacco into the shape of plugs, a plurality or tier of mold-frames

A, with intervening followers C may be placed in the press, as represented in Fig. 1 of the drawings.

To guard against injury to the follower by 5 severe contact thereof with the edges of the knives, I employ suitable stops for limiting the movement of the follower, which stops may consist of collars $f f$, adjustably secured to the press-rods $h h$ and engaging the under sides of plates $i i$, which are rigidly attached to and project laterally from the press-head P.

I do not limit myself to any special form 15 of the press, inasmuch as there are numerous presses of various constructions adapted for practicing my invention.

What I claim as my invention is—

The mold-frame provided with two sets of knives disposed at right angles to each other within said mold-frame and the follower entering into the mold-frame and provided with creases in its under side and coinciding with the knives, in combination with the horizontal press-bed supporting directly upon it the mold-frame and its knives and forming the bottoms of the pockets formed between the knives, and the press-head detached from the follower substantially as set forth and shown.

RICHARD E. ELLIS.
